UNITED STATES PATENT OFFICE.

JOHN HOLTZMAN, OF NEW YORK, N. Y., ASSIGNOR OF ONE-HALF TO BENJAMIN ROMAN, OF NEW YORK, N. Y.

RAZOR-BLADE-SHARPENING MACHINE.

Application filed May 27, 1921. Serial No. 473,052.

This invention relates to razor blade sharpening machines and particularly to the type that is utilized for sharpening double-edged flexible safety-razor blades, such as are used in connection with the well known "Gillette" razors.

The principal object of the invention is to provide a simplified, inexpensive, conveniently and economically manufacturable, conveniently operable and utilizable, light, compact, strong, durable, efficient and improved razor-blade sharpening machine of the above mentioned character.

Other objects and advantages will hereinafter appear.

In the accompanying drawings,—

Fig. 1 shows a cross-sectional elevation of the razor-blade sharpening machine.

Fig. 2 is a sectional plan view of the machine shown in Fig. 1.

Figs. 3 and 4 show details of the machine.

Upon the axle 1 is fixed a sharpening roll 2, which comprises a core 3 made preferably of wood, an exterior layer or rim 4 made of any suitable material or composition that affords an efficient sharpening, honing, or stropping surface, such as rubber, leather, etc., and a mutilated or hollowed out portion 5. The axle 1 is rotatably mounted in bearings 6 of the casing 7 of the machine, whereby the roll 2 is free to rotate in any direction. Directly under the roll 2 is located a drive-shaft 8, which is rotatably mounted in bearings 9 of casing 7, and to the shaft 8 is secured a crank 10 and handle 11, whereby revolving of the crank in either direction will freely rotate said drive-shaft accordingly. A pinion 12 is keyed upon the

axle 1, an idler-gear 13 is mounted upon a stud 14 secured to the wall of casing 7, and a pair of similar gear-segments 15, 16 are keyed upon the drive-shaft 8 and are thereon disposed opposite to each other in the manner shown. The idler 13 is in constant mesh with the pinion 12, the gear-segment 15 alternately meshes with and unmashes from the pinion 12, and the gear-segment 16 similarly meshes with and unmashes from the idler 13.

As the crank 10, therefore, is revolved in a clockwise direction as viewed in Fig. 1, the gear-segment 15 meshes with the pinion 12, and, due to the ratios of their diameters, rotates it together with the roll 2 two revolutions in the direc-

tion of the arrow. At the end of these two revolutions, the gear 15 unmashes from the pinion 12, and simultaneously the gear-segment 16 commences to mesh with the idler 13 and therethrough transmits a reverse rotation to the pinion 12, which thereby rotates together with the roll 2 two revolutions in an opposite direction to that of the arrow. As the revolving of the crank 10 is continued, this operation of the roll 12 is thus continuously repeated, viz., the roll performs two rotations in the direction of the arrow, then two rotations in an opposite direction, then again two rotations in the direction of the arrow and two rotations backwardly, etc.

Above the roll 2 is located a blade-holder 17, which is rotatably mounted in bearings 18, 19 Fig. 4, of the casing 7. Said blade-holder comprises a shaft 20, the extremities 21, 22 of which are journaled in said bearings 18, 19 respectively, a cut-out flattened portion 23, and a bar 24 which is pivoted to the shaft 20 at 25 and has an extremity 26 which fits into a recess 27 formed in the shaft-journal 22. The double-edged flexible safety-razor blade 28, which is to be sharpened, is inserted into the blade-holder 17 and held thereby, by means of placing it upon the flat face 23, of shaft 20, with its openings 29, that are provided in the "Gillette type" blades, slipping over a pair of pins 30 projecting from the shaft-face 23, and then the bar 24 may be swung about its pivot 25 to a position against the blade, as shown. The bar 24 is securely locked in place by means of its extremity 26 passing through a guide-slot 31, formed in the casing 7, and into the recess 27 of shaft-journal 22, and a strap 32 pivoted at 33 passing over said journal to complete the break in the bearing 19 produced by the slot 31. When the bar 24 is in the locked position shown, the pins 30 pass into recesses 34 formed therein. To remove the blade 28 from its holder 17 it merely requires swinging back the strap 32 to release the bar extremity 26 and then swinging the bar 24 upwardly about its pivot 25.

Upon the blade-holder shaft 20 is keyed a star-wheel 35 that comprises a pair of oppositely disposed gear-sectors 36, 37 and a pair of oppositely disposed cam portions 38, 39 that are located intermediately between the gear-sectors 36, 37, and upon the

roll axle 1 is keyed a cam-wheel 40 provided with a gear-sector 41 which is located opposite to the mutilated portion 5 of the sharpening roll 2. As the roll 2 performs its 5 rotation in the direction of the arrow its shoulder 42, which is suitably configurated, strikes the blade 28 and flexes it in the manner shown, thereby causing its edge 43 to land upon the roll and to exert pressure of 10 its edge-side 44 against its periphery, so that as the roll rotates it effectively sharpens this edge-side. During this sharpening operation, the blade 28 is maintained fixed, in the operative position shown, by the cam- 15 portion 38 of star-wheel 35 bearing against the periphery of the cam-wheel 40. When the cam-portion 38 and wheel 40 are thus in engagement with each other they maintain the unflexed portion of the blade radially to the axial center-line of the roll, but 20 preferably a clearance is provided, between said cam-portion and wheel, which permits disposition of the blade 28 at an angle from perpendicularity, as shown, in order to 25 bring the edge-side 44 into proper sharpening tangency with the roll 2 without unduly flexing the blade. Upon completion of the 30 first full revolution of the roll 2 the gear sector 41 meshes with the gear-sector 36 and imparts to the wheel 35 half a revolution, 35 bringing its cam-portion 39 in engagement with the wheel 40. This reverses the blade 28 and causes its opposite portion 45 to be flexed, in the above described manner, there- 40 by subjecting its diagonally opposite edge-side 48 to operative sharpening pressure against the roll-periphery, so that, as the roll rotates, it effectively sharpens this side. In its reversal, the blade 28 is not obstructed by the roll 2, due to the blade-portion 45 45 passing through the mutilated portion 5 of the roll. At the completion of the second revolution of the roll 2, its rotation is reversed, as above described, in a direction opposite to that of the arrow; and at the commencement of the third revolution the gear-sector 41 meshes with the gear-sector 37 and thereby imparts an approximately quarter revolution to the blade holder and bringing 50 the blade-portion 45 back into the mutilated portion 5 of the roll. As the roll 2 now performs its third rotation in an opposite direction, its shoulder 42^a, which is configurated similarly to the shoulder 42 strikes 55 the blade and flexes it in an opposite direction from that shown, whereby its edge-side 46 is brought to exert pressure against the roll-periphery and the roll sharpens this edge-side as it rotates. At the commence- 60 ment of the fourth revolution of the roll 2 the blade is again reversed and its fourth edge-side 47 is brought to bear against the roll-periphery, and as the roll performs its fourth revolution it accordingly sharpens 65 this edge-side effectively.

It will be evident that for each full revolution imparted to the operating crank 10, the roll 2 will sharpen each of the edge-sides 44, 48, 46, 47 of the blade 28 successively, and as the revolving of the crank is continued the sharpening of all the four sides of the two edges of the blade is continuously repeated, until the razor-blade thus becomes completely and efficiently sharpened. When the sharpening of the razor-blade is completed, the same may be readily removed from the machine and another blade may be inserted in the holder 17, and a similar sharpening operation may be performed thereupon. It will be evident that 80 any other type of blade-holder may be here utilized in place of the blade-holder 17 illustrated in Figs. 3, 4.

It will be noted that this machine is universal in its operation, in that, after mounting the blade in the holder 17, the crank 10 may be revolved in either direction for performing the sharpening operation. But if it is desired that the crank should be operated in one direction only, the same can be 90 readily done by simply providing that the crank be secured to the drive-shaft 8 by means of the thread 49, in which case, if revolving of the crank in an anti-clockwise direction should be attempted, it would unthread itself without affecting the machine in any way. When operating the machine the same may be either held entirely in one hand and its crank turned with the other hand, or the machine may be held against 100 a table in the position shown or placed upon a table with one of its sides 50 thereagainst. The upper portion of the casing 7 is preferably formed as a cover 51, which is hinged to the remainder of the casing at 52.

Variations may be resorted to within the scope of the invention and portions of the improvements may be used without others.

Having thus described my invention, I claim:—

1. A sharpening machine for double-edged razor blades having the combination of a rotatable sharpening roll, a blade holder, a drive shaft, mechanism to rotate said roll alternately in opposite directions while said shaft is driven in one direction, and said mechanism actuating said blade holder to dispose the four edge-sides of the blade to said roll; said mechanism including a pair of gear-segments, a pinion driven by one of said segments to rotate said roll, and a pinion driven by the other of said segments to rotate said former pinion to rotate the roll in an opposite direction.

2. A sharpening machine for double-edged razor blades having the combination of a sharpening element, a blade holder, a drive-shaft, mechanism to actuate said element alternately in opposite directions while said shaft is driven in one direction, and said

mechanism actuating said blade holder to dispose the four edge-sides of the blade to said element; said mechanism including a pair of gear-segments, a pinion driven by one of said segments to actuate said element, and a pinion driven by the other segment to rotate said former pinion to actuate said element in an opposite direction.

3. A sharpening machine for razor blades having the combination of a sharpening roll, a blade holder, a drive-shaft mechanism to rotate said roll alternately in opposite directions while said shaft is driven in one direction, said mechanism actuating said blade holder to dispose the edge-sides of the blade to said roll, and said mechanism including a pair of gear segments, a pinion driven by one of said segments to rotate said roll, and a pinion driven by the other 15 of said segments to rotate said former pinion to rotate the roll in an opposite direction.

4. A sharpening machine for razor blades having the combination of a sharpening element, a blade holder, a drive-shaft, mechanism to actuate said element alternately in opposite directions while said shaft is driven in one direction, said mechanism actuating said blade holder to dispose the edge-sides of the blade to said element, and said mechanism including a pair of gear-segments, a pinion driven by one of said segments to

actuate said element, and a pinion driven by the other segment to actuate said element in an opposite direction.

5. A razor blade sharpener having the combination of a rotatable sharpening roll, means to hold the blade in operative sharpening position, a drive-shaft, mechanism for rotating said roll being adapted to rotate the roll in opposite directions while said shaft is revolved in one direction; said mechanism including a pair of gear-segments on said shaft, a pinion on said roll meshing with one of said gear-segments, and an idler gear meshing with said pinion and 45 the other of said segments.

6. A razor blade sharpener having the combination of a sharpening roll, blade holding means, a drive shaft, and mechanism for rotating said roll alternatively in 50 opposite directions while said shaft is revolved in one direction; said mechanism including a pair of gear-segments driven by said shaft, means to transmit rotation to said roll from one of said segments, and 55 means to transmit opposite rotation to said roll from the other of said segments.
